KARL DRESSLER, OF GROSS SCHONAU, GERMANY, ASSIGNOR TO ISRAEL MOSES LERCH,
OF LEIPZIG, GERMANY

METHOD OF SECURING BUNDLES OF BRISTLES IN THE BODIES OF BRUSHES

Application filed April 29, 1927, Serial No. 187,674, and in Germany May 7, 1926.

This invention relates to a process for securing bristles collected together in the form of bundles in the body of a brush for the purpose of manufacturing brushes and it relates particularly to the manufacture of brushes in which the parts which receive the bristles are composed of pressable material such for example as malleable metal. According to the invention the bundles of bristles are secured in the bundle holes in the brush body which consists of compressible raw material by proceeding in the following manner. A pressing or stamping tool having a wide and flat pressure surface is caused to exert its pressure on to the body of the brush to begin with only at an annular distance from the bundle hole. The surface of the pressure tool is caused gradually to approach nearer to the base 20 of the bundle hole as the tool advances further, as is shown in Fig. 7.

This may be achieved for example by causing the edge of the bundle holes to be removed by substantially rounding or de- 25 pressing the same or by providing annular projections around the bundle holes, whilst at the same time correspondingly rounding off their edges. The result of the process according to the present invention is that on application of pressure the material of 30 the brush body which is malleable, forces the metal to constrict the bundle hole. In this way a constriction of the bundle hole which is substantially uniform throughout 35 is obtained. The edge of the hole is not sharp, so that the bristle bundles are not subjected to the risk of damage by sharp edges whilst being firmly and tightly held in order that liquid or dirt may not be able 40 to penetrate into the body of the brush.

Fig. 1 is a fragmentary transverse elevation of a brush blank;

Fig. 2 is a fragmentary transverse elevation of the same, showing the bristles in- 45 serted in the bundle hole;

Fig. 3 is a section similar to Figures 1 and 2, showing the action of the pressure tool;

Fig. 4 is a fragmentary sectional eleva- 50 tion of a modified form of brush blank;

Fig. 5 is a fragmentary sectional elevation of the same, showing the bristles in place;

Fig. 6 is a section similar to Figures 4 and 5 showing the action of the pressure tool;

Fig. 7 is a fragmentary transverse sectional elevation of a finished brush imme- 60 diately before the pressure tool is removed.

Two examples of methods of carrying out the invention are illustrated in the accompanying drawings.

Figures 1 and 4 illustrate the body of a brush having bundle holes *c* for the insertion of bundles of bristles, the form indicated by I having a substantially rounded portion *d* at the edge of the bundle hole *c*, whilst that designated II has an annular projection *d*¹ surrounding the bundle hole. 65

Figures 2 and 5 show that the bundle *f* together with an anchoring device *e* has been threaded through the pressure tool *b* into the hole *c* by means of a needle not illustrated in the drawings and previously used in other processes. After the needle has been withdrawn the pressure tool exerts a pressure on the brush body *a* as shown in Figures 3 and 6, and by means of its wide and flat pressure surface it compresses the material of the brush body in an annular 80 formation around the hole, whereby the latter under-goes a deeply penetrating constriction whilst at the same time a new and slightly rounded edge is formed around the hole, the said edge not damaging the bristles. Thereupon the pressure tool *b* is raised and sets free the bundle *f* which latter is now quite tightly enclosed and held in the hole *c*¹; in the example designated I the bundle is surrounded by an annular de- 85

pression *g* corresponding to the pressure surface of the pressure tool, whilst in the example designated II it is surrounded by a flat surface *g*¹. Figure 7 shows on a much enlarged scale the operation of the pressure tool. After the bundle *f* has been inserted together with an anchoring device *e* through the pressure tool *b* into the bundle hole *c* in the brush body *a* the pressure tool *b* with its flat pressure surface compresses the ma- 90

terial surrounding the edge of the hole d in a downward direction, this material being displaced in the direction of the arrows towards the interior of the hole c^1 , thus causing a deep going constriction of the bundle hole; whilst the walls of the hole remain smooth and a new and rounded edge is formed around the hole.

Having now particularly described and ascertained the nature of my said invention and in what manner the same is to be performed, I declare that what I claim is:—

1. A process for the manufacture of bristle brushes which consists in forming a multiplicity of sockets in a piece of metal the thickness of which is greater than the depth of the sockets and sufficient to adapt it for use as a brush body, each of said sockets having a well rounded edge, inserting a bundle of bristles in each of said sockets, and applying to an annular surface around each socket pressure sufficient to cause lateral displacement of metal substantially throughout the depth of the socket, and thereby form a socket entirely below the plane of the upper surface of the body which socket has a rounded edge and securely grips the bundle of bristles throughout its depth.

2. A process for the manufacture of bristle brushes which consists in forming a multiplicity of sockets in a piece of metal the thickness of which is greater than the depth of the sockets and sufficient to adapt it for use as a brush body, each of said sockets having a well rounded edge surrounded by a raised annulus integral with said body, inserting a bundle of bristles in each of said sockets, and applying to said annulus pressure sufficient to cause contraction of the bore of the socket substantially throughout its depth, and thereby form a socket entirely below the plane of the surface of the brush body, said socket having a rounded edge and being in gripping engagement with the bundle of bristles throughout its depth.

In testimony whereof I have affixed my signature.

KARL DRESSLER.
